UNITED STATES PATENT OFFICE

CHARLES F. LAMBERT, OF GROSSE POINTE FARMS, MICHIGAN, ASSIGNOR TO CLAYTON AND LAMBERT MANUFACTURING COMPANY, OF DETROIT, MICHIGAN, A CORPORATION OF DELAWARE

DESIGN FOR A TIRE COVER FOR SPARE TIRES

Application filed September 28, 1932. Serial No. 45,103. Term of patent 14 years.

To all whom it may concern:

Be it known that I, CHARLES F. LAMBERT, a citizen of the United States, residing at Grosse Pointe Farms, in the county of Wayne and State of Michigan, have invented a new, original, and ornamental Design for a Tire Cover for Spare Tires, of which the following is a specification, reference being had to the accompanying drawing, forming part thereof.

Fig. 1 is a perspective view of my tire cover with the front half thereof exposed.

Fig. 2 is an end elevation of the cover, partly in section, and showing both the elevational and cross-sectional contour thereof, including the general location of the circumferential ornamental bead.

I claim:

The ornamental design for a tire cover for spare tires, substantially as shown.

CHARLES F. LAMBERT.
